(57) **CLAIM**

The ornamental design for a power surge protector, as shown and described.

DESCRIPTION

FIG. 1 is a perspective view of an aspect of our new design; FIG. 2 is a front view thereof;

FIG. 3 is back view thereof;

FIG. 4 is a left side view thereof;

FIG. 5 is a right side view thereof;

FIG. 6 is a first end view thereof; and

FIG. 7 is a second end view thereof.

The ornamental design that is claimed is shown in solid lines in the drawings. The broken lines in the drawings are for illustrative purposes only and form no part of the claimed design.
